PORTABLE GRENADE GUN

Cleve F. Shaffer, San Francisco, Herman J. Fanger, Piedmont, and Henry Gruenhagen, Oakland, Calif.

Application May 25, 1942, Serial No. 444,350

5 Claims.

(Cl. 42—1)

This invention relates to muzzle loading guns of the type used for firing grenades instead of throwing them by hand, and the principal object of the invention is to provide improvements in this type of gun whereby it will be more compact and easily carried and operated by infantrymen. Also special features and advantages of the invention will appear in the following description and accompanying drawing.

In the drawing:

Fig. 1 is a side view of our improved grenade gun outfolded or extended to firing position and with portions broken away to reveal the inner structure.

Fig. 2 is a side view of the gun folded up to about half its length, and as seen from right angles to the view of Fig. 1.

Fig. 3 is an enlarged cross sectional view of the gun of Fig. 1 as seen from the line 3—3 thereof.

Fig. 4 is an enlarged central vertical section of the base of the gun barrel, firing chamber, and associated parts, as well as one of the pivots about which the barrel swings in folding up.

Briefly stated the gun comprises a muzzle loading barrel adapted to receive a grenade mounted on an adapter. The barrel is pivoted to the outer end of a skeleton stock or shoulder frame in a manner to swing around and fold up in the frame, and the barrel of the gun then forms a receptacle for several grenades and/or grenade adapters as the open end of the muzzle is closed when the gun is folded. The gun is fired with a finger set and released firing pin, so that the utmost simplicity is maintained throughout the structure to make the gun substantially fool proof and not likely to get out of order in the field.

In the drawing 1 is the gun barrel, 2 the base or firing chamber member to which the barrel is attached, and which base member is pivoted on a transversely extending axis 3 by means of pivots 4, to the upper end or ends of a skeleton frame 5 in turn secured at its lower end to a disk 6 covered on the outer side by a very thick piece of cellular rubber 7 or other resilient shock absorbing pad such as felt, or any suitable combination of resilient materials so as to form a pad adapted to go against the shoulder of the person firing the gun.

The gun has a centrally disposed firing pin 8 at the bottom of the firing chamber, and is adapted to fire any muzzle loading projectile carrying its own ejection charge, but is particularly constructed and adapted for firing hand grenades mounted on bore fitting adapters which carry their own expelling cartridge at the lower end so that it will come over the firing pin when slid down the bore of the gun, such grenade adapter assemblages as are particularly shown

and described in the copending concurrently filed patent application of Herman J. Fanger bearing Serial #444,307 and which application shows and claims a grenade adapter provided with 5 spring detents which engage under an annular shoulder 9 formed around the firing chamber, and also the special curved reflecting form of the base of the firing chamber indicated in Fig. 4 at 10.

10 The gun barrel 1 is preferably screwed to the base 2 as by the threads 11, and the lower end of the barrel is thickened as at 12 and is castellated as at 13 where it tapers off to the barrel thickness, so that a soldier desiring to unscrew the barrel to clean out the firing chamber can strike the edges of the castellations with any hard heavy object either to start the unscrewing, or similarly to finally screw the parts tightly together.

15 The base 2 is round, and of somewhat larger diameter than the barrel and has two arcuate ears or extension 2' extending downward and to which the stock frame sides 5 are respectively pivoted by the pivots 4. The form of the side members 5 and their relation to the base 2 of the barrel is best shown in Fig. 3. The frame sides 5 are of sheet metal arcuately channelled to fit against the opposite sides of the base member 2 and are outwardly beaded along their edges as at 5' to stiffen them, and each one has a short reinforcing plate 5'' spot welded to the outer side of its upper end where the pivot goes through. The pivots are free to turn in the frame members and free to slide and turn in the ears 2' and are resiliently urged inwardly by heavy compression springs 14 reacting between the ears 2' and collars 15 on the pivots, the collars are kept from coming off of the pivots by any suitable means, such as by slightly heading over the inner ends 20 of the pin as at 16. The outer ends of the pivots are provided with relatively large heads 4'.

25 The lower ends of the frame sides are preferably welded to a downwardly extending flange 6' formed around disk 6, and the pad 7 is cemented, vulcanized or otherwise firmly secured to the underside of the disc, its flange, and the adjacent ends of the frame sides.

30 By the construction thus far described it will be manifest that the stock frame 5 the resiliently clamped against opposite sides of the base 2 by the springs 14, may be forcibly swung on axis 3 by grasping the frame with one hand and the gun barrel with the other, as the springs will yield to permit sufficient spreading apart of the frame sides to permit the base 2 to turn out of its arched seat, and as the diameter of the gun barrel is just within the space between the frame sides it may be swung clear around with its muzzle close to disk 6, and hence if desired its bore 35 may be used as a storage receptacle for several

grenades and their adapters, by soldiers on the march, any suitable strap or sling being provided to carry the folded gun on the shoulder.

When the gun is extended or outfolded it will be rigid if springs 14 are strong, but to guard against doubling up through faulty handling or using, any suitable latch may be used or split pin as at 17 shoved through a hole in the frame and one of the ears 2. The split pin may be on the end of a short chain 18 secured at its other end to the frame as at 19.

The finger operated firing pin includes a tubular housing 20 screwed over a threaded boss 21 projecting from the underside of the base 2 of the barrel. The firing pin 8 slides in a hole 22 drilled through the bottom of the firing chamber member or base 2 and is shown provided with an enlarged head 23 slidably in a bore 24 in the housing 20 and normally urged outwardly against a shoulder 25 by a very light compression spring 26 to retain the firing pin in retracted position with its free end just below the firing chamber as shown.

Outward of firing pin head 23 is a trigger or hammer pin 27 of a diameter somewhat smaller than head 23 and freely slideable in a bore 28. Pin 27 is hollow at its outer end as at 29 and within it is a strong spiral compression spring 30 urging the hammer pin toward the head 23 of the firing pin, but pin 27 is limited in its forward movement by any suitable stop while its blow upon the head 23 of the firing pin will drive the latter forward by momentum until it strikes the outer end of boss 21 with the free end of the firing pin extending into the firing chamber (to explode the cap of the ejecting cartridge of the projectile used), still the hammer pin 27 is stopped in its forward movement at a point which will always permit the firing pin to be retracted from the firing chamber by light spring 26, or in the absence of this spring the pin will fall back by gravity if the gun be pointed upwards, or it will be pushed back by the cartridge of the projectile slide into the gun barrel, without exploding the cap.

In Fig. 4 the stop for the forward movement of the hammer pin 27 is of a transversely extending finger pin or trigger 31 which passes tightly through pin 27 and projects at both ends through a slot 32 cut through the housing 20. This slot is laterally notched at its outer end as at 33 so that when trigger pin 31 is grasped by two fingers and pulled back and compress spring 30, the pin 31 is swung laterally into the notches 33 to "cock" the trigger, and to fire the gun the trigger pin is simply pushed out of the notches to fly forward under the suddenly released energy of spring 30 and cause pin 27 to strike a quick blow on the head 23 of the firing pin, to in turn, drive it forward as explained, but since the trigger pin 31 comes to the inner end 32' of slot 32 it cannot follow up the firing pin, and always permits the latter to be backed out of impinging contact with the cartridge cap.

In the drawing the spring urged hammer pin is shown as just at the point of striking the head of the firing pin, and with the trigger pin 31 not yet at the ends of slot 32 which will stop its further motion, while the firing pin continues on.

With the above construction there is no danger of premature firing upon reloading from the muzzle as required with this type of gun, or when

the barrel is used as a transporting receptacle for several grenades and adapters with the gun folded, but it is evident that instead of the firing pin and hammer being in two sections, the inner or firing pin section may be an integral continuation of the hammer pin if greater simplicity is desired, and if the spring is relatively weak, the cap of a freshly inserted charge would still push the firing pin back without exploding the cap, in a case where the trigger was left in the discharged position.

Having thus described our improved portable grenade gun, what we claim is:

1. A muzzle loading grenade gun comprising a barrel closed at its inner end, a stock frame transversely pivoted at one end to the inner end of the barrel, said stock frame being of opensided construction permitting the barrel to fold on its pivotal connection and swing into the frame, and a shoulder piece on the opposite end of said stock frame including a member substantially closing off the muzzle of the gun when so folded into the stock frame, so as to retain grenades and/or adapters within the barrel.

2. A grenade gun having a barrel with a firing chamber at its inner end, a stock frame having two longitudinally extending side members spaced laterally and at one end embracing opposite sides of the firing chamber of the barrel, a disk tying the opposite ends of said members together, and means pivoting said side members to the firing chamber on an axis extending transversely of the gun barrel, and said stock frame being of such a length whereby the barrel may be folded on its pivotal connection into the space between said members with the end of its muzzle in confronting relation to said disk when the barrel is so folded.

3. In the construction as set out in claim 2, said disk provided with a downwardly extending marginal flange secured to the ends of said members, and a shoulder pad secured to the under side of said disk and embracing said flange.

4. In the construction set out in claim 2, said side members formed of sheet metal longitudinally channelled in a manner to snugly embrace the opposite sides of the firing chamber portion of the gun barrel when the gun is outfolded, and the means pivoting the members to the firing chamber including springs permitting the side members to spread apart as the barrel is being folded, and to close in against the firing chamber again when the gun is in folded position, thereby firmly holding the barrel in both folded and outfolded position.

5. In the construction set out in claim 2, said side members formed of sheet metal longitudinally channelled and stiffened by outward beading along its edges in a manner to snugly embrace the opposite sides of the firing chamber portion of the gun barrel when the gun is outfolded, and the means pivoting the members to the firing chamber including springs permitting the side members to spread apart as the barrel is being folded, and to close in against the firing chamber again when the gun is in folded position, thereby firmly holding the barrel in both folded and outfolded position.
